CLAIM

The ornamental design for an electric scooter, as shown and described.

DESCRIPTION

FIG. 1 is a front perspective view of an electric scooter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of portion 8 shown in FIG. 1; and,

FIG. 9 is an enlarged view of portion 9 shown in FIG. 1.

The broken lines shown in the drawings represent portions of the electric scooter and form no part of the claimed design.
